[57] CLAIM

The ornamental design for a wire channel, as shown and described.

DESCRIPTION

FIG. 1 is a perspective view of the wire channel taken from the side and one end showing my new design;

FIG. 2 is an opposite end elevational view thereof.

The trunking comprises an elongate channel member and a snap-fit cover member. The channel is secured to a substrate such as a wall, and services, such as electric and telephone cable, laid therein before the cover is fitted thereof.
